US0D1010966S

(12) United States Design Patent (10) Patent No.: US D1,010,966 S
(45) Date of Patent: * Jan. 9, 2024

(54) BEACH CART WHEEL

(71) Applicant: MAXTON ENGINEERING LTD.,
Hong Kong (CN)

(72) Inventor: Shou Qiang Zhu, Ontario, CA (US)

() Term: 15 Years

(21) Appl. No.: 29/784,169

(22) Filed: May 18, 2021

(51) LOC (14) Cl. 12-02

(52) U.S. Cl.

USPC D34/27

(58) Field of Classification Search

USPC D34/12, 16, 18, 23, 24, 27; D12/204,

D12/210, 211, 501; D21/563, 779

CPC B60B 5/02; B60B 3/001; B60B 2310/204;
